UNITED STATES PATENT OFFICE.

JOHN D. MENG, OF ROCHESTER, NEW YORK.

VENDING MACHINE.

Application filed January 2, 1923. Serial No. 610,163.

To all whom it may concern:

Be it known that I, JOHN D. MENG, a citizen of the United States, residing at Rochester, in the county of Monroe and 5 State of New York, have invented certain new and useful Improvements in Vending Machines, of which the following is a specification.

The object of this invention is to provide 10 a new and improved vending machine which is especially adapted to vend small cylindrical packages containing powdered soap.

These and other objects of this invention 15 will be fully illustrated in the drawings, described in the specification and pointed out in the claims at the end thereof.

In the accompanying drawings:

Figure 1 shows a front elevation of the 20 vending machine.

Figure 2 shows a side elevation of the vending machine with the door on the side of the machine being removed to show the operating mechanism of the machine.

25 Figure 3 shows a horizontal sectional view of the vending machine, the section being taken on the line 3X—3X of Figure 1.

Figure 4 shows a vertical sectional view of the vending machine the section being 30 taken on the line 4X—4X of Figure 1.

Figure 5 shows a vertical sectional view of the vending machine the section being taken on the line 5X—5X of Figure 3.

Figure 6 shows a transverse sectional view 35 of the vending machine the section being taken on the line 6X—6X of Figure 3.

In the several figures of the drawings like reference numerals indicate like parts.

The vending machine forming the subject 40 matter of my present invention is especially adapted to dispense small individual packages containing powdered soap. These packages are cylindrical in shape and may be made of any material suitable for this 45 purpose. As will be described hereinafter the vending machine is provided with a magazine in which a number of these packages can be stored and dispensed by it one at a time by a suitable mechanism that can 50 only be operated after dropping a coin into the machine.

As illustrated in the drawings the magazine and dispensing mechanism are mounted in a suitable casing 1. For this reason the 55 casing 1 is high and narrow on the side in which the magazine is contained while the

part of the casing containing the operating mechanism which is located at one side of the magazine is not so high but has a greater depth so that it projects forwardly of the 60 part containing the magazine. The back 3 of the casing is provided with the slots 4 and 5 into which a pair of supporting hooks 6 and 7 are adapted to engage. These hooks are threaded into the wall on which the 65 vending machine is to be mounted and the casing thereof is locked to these hooks by means of the locking rod 8 mounted on the inside of the casing near the bottom thereof. The locking rod 8 is mounted to slide in a 70 suitable sleeve 9 mounted on the inside of the back of the casing. When it is desired to mount the casing to the wall this locking rod is withdrawn from below the hook 7 so 75 that this hook can be readily inserted into the slot 5 in the back 3 of the casing. When this is done the back of the casing is allowed to slide down the inclined back of the hook as illustrated in Figure 4 so that the locking bar 8 can be moved under the hook 80 7 by sliding it to the left into the position illustrated in Figure 3. A handle 10 is provided on the right hand end of the locking rod with which the rod can be moved as 85 above described and when the rod has been moved into the locking position this handle is placed between two pins 11 and 12. This prevents the locking rod from sliding out from under the hook 7 and thus holds the 90 hooks 6 and 7 in the position shown in Figure 4 in which the casing cannot be disengaged from them.

The magazine containing the packages is formed by a vertical duct 13 having cross 95 sectional dimensions corresponding to the diameter and length of the packages to be dispensed by the vending machine. Near the bottom of the casing the vertical duct 13 is enlarged to have the dispensing cylinder 14 mounted to rotate therein. This dispensing cylinder is carried on the end of the horizontal shaft 15 and supports the cylinder in line with the vertical duct 13 as illustrated in Figure 4. The dispensing cylinder is made up of a series of four semi-cylindrical 100 troughs 16, 17, 18 and 19. These troughs are grouped radially around the shaft 15 and each of them as it is moved under the duct is adapted to receive the bottom package contained therein.

The shaft 15 carrying the dispensing cylinder projects into the enlarged portion of 110

the vertical duct 13 from the right hand side of the casing 1 in which the operating mechanism is mounted. This operating mechanism of which the shaft 15 forms a 5 part is mounted in a suitable cradle 20 made up of sheet metal and having upturned flanges at the front and rear thereof with which the cradle can be supported within the casing on the pins 21, and 22 provided 10 on the inside walls of the casing 1.

On the cradle 20 is mounted the upright member 23 in which the bearing for the right hand end of the shaft 15 is provided. For the left hand end and intermediate support 15 of the shaft 15 the bracket 24 is provided. This bracket forms part of the cradle 20 and projects laterally from the left hand end of the cradle 20 with the bearing members 25 and 26 formed at the ends thereof. 20 The bearing in the bearing member 26 for the right hand end of the shaft 15 is a full bearing and after the end of the shaft has been engaged therein it cannot be lifted out therefrom except by an endwise movement 25 of the shaft 15. The bearing in the bearing member 25 however consists of a vertical slot so that after the shaft 15 has been disengaged from the bearing of the bearing member 16 it can be lifted out of the slotted 30 bearing provided in the bearing member 25. The upright member 23 in which the bearing for the right hand end of the shaft 15 is mounted has a base formed at the bottom thereof. This base is mounted to slide be- 35 tween the two guide rails 27 and 28 so that it can be adjusted laterally to the right position in which it is then clamped by means of the thumb nut 29. This thumb nut passes through the slot 30 provided in the base of 40 the upright so that the base can be moved to the right or left to the correct position and then clamped in place on the cradle.

Keyed to the shaft 15 at the right of the dispensing cylinder 14 is the connecting 45 wheel 31. This wheel is made up of a pair of circular discs 32 and 33. These discs are suitably spaced apart and each of them has a series of four short radial channels 34 formed in one side thereof with the channels 50 of one of the discs facing the channels of the other disc. Each pair of the short channels 34 located opposite to each other in the two discs of the connecting wheel thus forms a radial pocket in the connecting wheel which 55 is adapted to receive the coin that is dropped into the vending machine.

For the purpose of holding the pockets in the connecting wheel in line with the chute 35 in the casing 1 through which the coin is 60 inserted for the purpose of operating the machine, a locking cam 36 is provided keyed to the shaft 15. This locking cam comprises a four pointed wheel against two of which points is held a leaf spring 37. This spring 65 is bow shaped and at its intermediate part

bears against and holds the locking cam in a predetermined angular position and with it the shaft 15 so that one of the pockets provided on the connecting wheel 31 is always in line with the chute 35 of the casing. The 70 leaf spring is fastened at one end to the base of the cradle 20 while the other end is free to slide along the base to allow the intermediate part of the spring to be depressed by the locking cam when it is rotated as will 75 hereinafter be described.

Loosely mounted to swing on the shaft 15 between the locking cam 36 and the upright member 23 is the bell crank 38. One end of 80 this bell crank is provided with a pair of guide members 39 and 40 between which the inner end of the operating lever 41 may be clamped in place by means of the thumb nut 42. The other end of the bell crank carries a laterally projecting arm 43 on the 85 outer end of which is formed three upwardly projecting prongs 44, 45 and 46 and one downwardly projecting prong 47.

The arm 43 projects over the connecting 90 wheel, and the downwardly projecting prong 47 is adapted to project centrally between the circular discs of this connecting wheel. For this reason the bell crank 38 can be rocked by means of the operating arm 41 without disturbing the position of the connecting wheel as long as no coin is placed in a pocket of the connecting wheel. The downwardly projecting prong 47 is free to move between the two discs of the connecting wheel in the 95 absence of a coin. As soon as a coin is dropped into the machine and is located in the pocket of the connecting wheel held in line with the coin chute the downwardly projecting prong 47 encounters this connecting link formed by the coin placed between 100 the two discs of the wheel, so that on further rotation of the prong the wheel is turned with the bell crank and given nearly a quarter of a revolution on the lifting of the operating lever 41. During the rotation of the 105 connecting wheel by the operating lever the shaft 15 is rotated with it so that at one end of the shaft the locking cam 36 is turned through a corresponding angle. During 110 this angular movement of the locking cam one of the points of the locking cam depresses the leaf spring 37 until this point of the cam has been moved past the vertical axis of the cam when the pressure of the spring operates to force this point of the lock cam further in the direction in which 115 it had been turned until the following point of the locking cam rests on top of the leaf spring and arrests a further movement of the cam. During this rotation the connecting wheel as well as the dispensing cylinder is advanced one quarter of a turn so that 120 the succeeding radial pocket of the connecting wheel and the succeeding trough of the dispensing cylinder is moved into the posi-

tion of the pocket and trough originally in line with the coin chute and the magazine respectively.

When the vending machine is set up for operation a soap package must be placed in the trough of the dispensing cylinder facing the rear of the casing 1. This is necessary because in dropping a coin into the machine as above pointed out and then 10 operating the machine the dispensing cylinder is advanced but a quarter of a turn so that the soap package in the uppermost trough taken from the bottom of the magazine is moved to the position of the trough 15 facing the rear of the machine while the package in the trough facing the rear of the casing is moved to the lowermost position and the trough then drops its package of soap into the chute 48 and into the pocket 20 49 formed at the bottom of the chute. The package thus delivered is the one purchased for the coin dropped into the vending machine.

To prevent sheet steel or iron punchings 25 of the size and shape of a coin from operating the vending mechanism a magnet 50 is mounted on the inside of the casing just below and at one side of the coin chute 35. This magnet is of the horse shoe type and 30 is positioned above the connecting wheel so that the two upwardly projecting prongs 44, 45 and 46 pass by close to the outer and inner edges of the end of the magnet when the arm 43 is rocked on the upward movement 35 of the operating lever 41. When, therefore, a steel or iron slug is inserted into the machine and drops down the coin chute 35 the magnet will attract it as soon as it leaves the lower end of the chute and before 40 it has a chance to enter the pocket in the connecting wheel. On the operation of the operating lever 41 the upwardly projecting prongs of the arm 43 engage the slug from behind and force it away from the magnet 45 without allowing it to enter the pocket in the connecting wheel. The fake coin thus knocked off the magnet drops down into the bottom of the casing without forming the proper connection between the operating lever and connecting wheel so that on 50 the operation of the lever the vending machine is not actuated.

The casing of the vending machine is provided with a door 51 at the top of the maga-

zine through which the magazine is filled 55 with the packages.

A second door 52 is provided on the right hand side of the casing for the purpose of providing access to the vending mechanism. Through this door the whole of the operating mechanism may be removed from the casing and for this purpose this mechanism is mounted on the cradle 20 that is suspended from the sides of the casing by means of a sliding connection with the pins 21 and 22. 60 65

I claim:

1. In a vending machine, the combination of a magazine, a dispensing cylinder mounted in the bottom of said magazine, an operating mechanism adapted to rotate said dispensing cylinder, said operating mechanism comprising a shaft on which said dispensing cylinder is mounted, an operating wheel carried on said shaft having a circular channel centrally formed thereof and 70 coin receiving means, a locking cam carried on said shaft, a bell crank loosely mounted on said shaft, a laterally projecting arm carried by said bell crank, a prong formed on the end of said arm and projecting into 80 said circular channel of said operating wheel, said prong being adapted to engage a coin dropped into said coin receiving means, and means to rock said bell crank to swing said prong against the coin and advance said wheel with said coin. 75 85

2. In a vending machine, the combination of a shaft, a vending cylinder mounted on one end of said shaft, a locking cam carried on the other end of said shaft, a yielding member adapted to hold said locking cam in a predetermined position, an operating wheel mounted on said shaft intermediate of said vending cylinder and said locking cam, said connecting wheel comprising a 90 95 pair of discs, said discs formed with radially extending coin receiving channels, the channels of one disc facing the channels of the other disc, a rocking arm projecting over said operating wheel parallel with said shaft, a prong formed on said rocking arm and projecting radially between the channels of the two discs to move said connecting wheel through the medium of a coin dropped in a pair of said radial channels on 100 105 the rocking of said arm.

In testimony whereof I affix my signature.
JOHN D. MENG.
